UNITED STATES PATENT OFFICE.

ARTHUR I. FISCHER, OF CLEVELAND, OHIO, ASSIGNOR TO MORRIS H. GLAUBER, OF CLEVELAND, OHIO.

VITREOUS-CHINA COCK OR FAUCET.

1,424,562.

Specification of Letters Patent. Patented Aug. 1, 1922.

Application filed October 1, 1919, Serial No. 327,734. Renewed April 27, 1922. Serial No. 557,031.

To all whom it may concern:

Be it known that ARTHUR I. FISCHER, citizen of the United States, residing at Cleveland, in the county of Cuyahoga and State of Ohio, has invented certain new and useful Improvements in a Vitreous-China Cock or Faucet, of which the following is a specification.

This invention consists in a vitreous china cock or faucet in which the spout member and the valve body of the fixture are separate parts sleeved together and made of different materials, and in which the valve body is set as a metal fixture upon and in a base or basin slab and the spout member is surmounted by a cap adapted to provide a hand grip. The spout member and cap are preferably made of vitreous china, porcelain or glass, whereby the metal parts are completely enclosed to present a slightly appearance and afford a sanitary covering for the working parts which are constructed and adapted to operate substantially as herein shown and described. In such an assembly of parts the water is transferred from the body to the separate spout member and the object is to promote the assembly and disassembly of the parts, prevent leakage at the joints, and safeguard against strains and breakage of the weaker members made of vitreous material.

In the accompanying drawings, Fig. 1 is a side elevation of the complete fixture assembled, and Fig. 2 is a central sectional elevation thereof.

The details are shown in a series of separate views, in which Fig. 3 is a sectional elevation of the vitreous-china crown-shaped hand grip for rotating the valve stem; Fig. 4 is a perspective view of the ring nut which is adapted to be seated in the head of the spout over a gasket therein when engaged with the neck of the valve body. Fig. 5 is an elevation of the vitreous-china spout member, the head portion being in section. Fig. 6 is a perspective view of a packing nut adapted to enter into the top of the thimble, which is shown in vertical section in Fig. 7. Fig. 8 is a side view of the valve stem with a quick-thread corresponding to the thread in the thimble and adapted to open and close the valve with a quick action. Fig. 9 is a vertical section of the valve body with a flat gasket or sealing member seated upon its base flange.

Primarily, the inventive concept is to provide a cock or faucet which will show nothing but an exclusively white vitreous spout member and a white vitreous surmounting cap or handle by which the valve is operated.

The spout member 2 and the crown-shaped cap or bulbous handle 3 being of vitreous china, porcelain or equivalent material and preferably white in color, are in a sense breakable; therefor special means for securing them in operating position and connection with a valve body and working parts are essentially necessary. Hence the means herein shown, wherein the spout member is made with a rounded enlargement or head having a flat circular rim 4 adapted to rest directly upon a flat base or basin slab. The bottom side of this rounded enlargement is also made with an annular recess having a flat seat 5 adapted to hold a sealing gasket or washer 6 which in turn is adapted to rest upon the flat annular flange 7 of the metal body 8 for the valve parts. When compressed the washer or gasket 6 provides a water-tight joint at the bottom side of spout member 2, and a similar water-tight joint is obtained at the upper end or neck 9 of spout member through the medium of a rubber gasket or packing ring 10 adapted to be compressed within an annular seat 11 in neck 9 by a screw-ring or nut 12 engaged with the screw-threads about the upper end of body 8. The rounded enlargement of the spout member is open from top to bottom and formed with an inner chamber 14 open to the discharge passage of the spout, and the two gaskets prevent leakage from this chamber and also cushion and protect the vitreous body from contact with the metal part of the valve body.

Having this basic assemblage, the valve stem 15 and the parts associated therewith can be placed in position or removed without disturbing nut 12 or the spout as fixed upon body 8, and the stem has a quick-thread 16 on its lower portion engaged with like threads in a screw-sleeve or thimble 17 which is screwed into the upper end of body 8. A valve 18 on stem 15 is adapted to engage a valve seat 19 within body 8 beneath an opening or outlet 20 in the side thereof, and the top of said stem is angular to engage in a correspondingly-shaped cen-

tral opening in a metal bushing fixed in cap 3. A screw 21 secures cap 3 to stem 15, and the cap has a small recess 22 internally within which the exposed head of a packing nut 23 for stem 15 is adapted to extend. A skirting 24 also extends downwardly from the cap to cover and conceal thimble 17 and lock nut 12 in respect to which the cap rises and descends as it is rotated to open and close the valve. Normally the cap is down and overlaps the upper end or extension of the spout head or enlargement thus leaving none of the metal parts visible above the slab or base through which the screw-threaded pipe-connecting portion 26 of body 8 extends.

Thimble 17 is externally threaded in its lower portion and screwed into body 8 down to a slight collar or bead 25 about the upper portion thereof, while the thimble is also threaded internally just above this bead to receive the packing nut 23. Upon disengaging cap 3 from stem 15, thimble 17 can be reached and unscrewed from body 8 and the valve can then be removed from the thimble, all without disassembling the spout from the body or disturbing the setting of the body on its base.

What I claim is:

- 30 1. A cock or faucet comprising a metallic body having valve parts therein, a spout member of vitreous material having an enlargement enclosing said body and clamped in situ thereon, and a hand grip of vitreous material surmounting said valve parts and provided with a skirting surrounding a portion of said enlargement.
- 25 2. A cock or faucet, comprising a metallic body having a base flange, a spout member of vitreous material provided with an enlargement seated over said base flange, a nut engaging the top of said body and bearing upon said spout member, and compressible means interposed between said spout member and flange and said nut, respectively.
- 40 3. A cock or faucet comprising a tubular

body of metal having a neck with an outlet in its side, a spout member of vitreous material sleeved upon said neck, means adapted to make a fluid-tight connection between said body and spout member, a valve member operatively mounted within said body and provided with a stem, and a cap and hand grip of vitreous material operatively engaging the said stem and overlapping the upper sleeved portion of said spout member.

4. A cock or faucet consisting of a metal body having a screw-threaded neck at its top and a flange about the base of said neck, a spout member of vitreous material having a chambered head seated on said flange about the base of said neck and united in water-tight relation at the joints therewith, a thimble threaded into said neck having a quick internal thread, a valve having a stem rotatably engaged with said thread, and a hand-grip fixed to said valve stem having a skirting surrounding the upper portion of the head of said spout.

5. A cock or faucet, comprising a tubular metal body having an external flange and an internal valve seat and provided with a discharge opening in its side opposite said valve seat and screw-threaded at its opposite ends, a vitreous china spout having an enlargement with a recessed bottom adapted to seat on and cover said flange and provided with a central water-distributing chamber and an upper annular seat for a gasket, sealing members for said seats, a nut screw-engaged with said body adapted to clamp the vitreous china spout and metal body together, a valve member removably mounted within said metal body opposite the valve seat, and a bulbous recessed vitreous china handle secured to said stem in covering relation to the spout enlargement.

Signed at Cleveland, in the county of Cuyahoga, and State of Ohio, this 26th day of August, 1919.

ARTHUR I. FISCHER.
